Specification for Design.

Patented Dec. 23, 1919.

Application filed October 4, 1919. Serial No. 328,596. Term of patent 14 years.

To all whom it may concern:

Be it known that I, FRED E. BURRALL, a citizen of the United States of America, residing at Green Bay, in the county of Brown and State of Wisconsin, have invented a new, original, and ornamental Design for a Tire-Tread, of which the following is a specification, reference being had to the accompanying drawing, forming a part thereof.

Figure 1 shows a perspective view of the tire tread illustrating my new design.

Fig. 2 is a sectional view thereof.

I claim:—

The design for a tire tread, substantially as shown.

FRED E. BURRALL.
